UNITED STATES PATENT OFFICE.

ELBERT MONROE TOLSTON, OF MACON, GEORGIA.

RAILWAY-CROSSING SIGNAL.

Application filed December 11, 1919. Serial No. 344,010.

To all whom it may concern:

Be it known that I, ELBERT MONROE TOLSTON, a citizen of the United States, residing at Macon, in the county of Bibb and 5 State of Georgia, have invented certain new and useful Improvements in a Railway-Crossing Signal, of which the following is a specification.

This invention appertains generally to 10 train controlling apparatus and more particularly to railway crossing signals.

The primary object of the invention is to provide a simple, reliable, and effective signalling mechanism whereby the signal will 15 be automatically given by a train approaching a crossing in either direction and said signal being thrown out of operation when the train is on the crossing and also when it is departing from the crossing.

20 This object is accomplished by providing a signal circuit and a switch operating circuit whereby the switch will permit the switch operating circuit to be closed while the train is departing from the crossing.

25 Other objects and advantages of the invention will become apparent during the course of the following description.

In the accompanying drawing forming a 30 part of the application and wherein like numerals are employed to designate like parts throughout the several views,

35 Figure 1 represents a diagrammatic plan view of an electric railway crossing signal embodying this invention and showing all of the circuit wire connections.

Figure 2 is a side elevation of the switch and motor constituting a part of this invention.

40 Figure 3 is a detail plan view of the switch.

Figure 4 is a front elevation of the upper portion of one of the signal carrying posts, and

45 Figure 5 is a side elevation thereof.

50 In the embodiment illustrated, three separate portions or blocks of a railway track are shown at A, B and C, block B being the portion of the track at the crossing and blocks A and C those at opposite sides of the crossing or other points at which signals are desired. The track sections or blocks have their continuous portions separated or insulated as shown at a whereby each of said blocks may remain on a separate and independent circuit. It will, of

course, be understood that the separate sections or blocks A and C on opposite sides of the crossing section B are of sufficient length to insure operation of the alarm by a train approaching from either direction. The ends of said sections remote from the crossing section B are of course insulated from the remainder of the track by the usual insulation, said insulation being also shown at "a" in the drawing in Figure 1. 60

In carrying out the invention two signal posts 1 are arranged on opposite sides of the track and on the highway, each carrying an electric light bulb 2 at its top, a signal box 3 supported on the post below 70 said bulb and having a transparent face 4 containing any desired warning, that shown being the words, "Danger stop." An electric bulb 5 is mounted in the box 3 to illuminate the face 4 thereof to render the 75 warning contained thereon visible at night. Carried by a post 1 and preferably arranged below the box 3 is an electric bell 6 which is in the same circuit with the lights 2 and 5 so that all of them will be actuated 80 simultaneously.

Suitably located adjacent the crossing, is a switch 10 in the form of a knife blade switch having the usual base 11, lever carrying posts 12, lever receiving sockets 12, 85 and a lever 13 hinged to the carrying posts 12 and adapted to be raised and lowered for opening and closing the switch. This lever 13 carries an extension 14 at its arched end composed of insulating material and having contact arms 15 and 16 extending laterally from opposite sides thereof. Carried by these arms 15 and 16 are two contact plates 17 and 18, one of which is electrically connected with a motor 50 by a conductor 95 wire 9, and the other with the battery B' by the wire 9^a. The wires 9 and 9^a are included in the motor or switch controlling circuit which is connected to the track sections B at the crossing by wires 22 and 23. 100 It will of course be understood that each wire 22 and 23 is connected to corresponding rails of the two track sections B which is clearly illustrated. The wire 22^a is connected to the wire 9, by wire 22, while the wire 23 is connected to wire 9^a by wire 23^a as clearly shown. Consequently when the train reaches either track section B, the switch operating circuits will be closed 105 through the engine thereby causing the 110

motor 50 to operate to lift the switch lever in a manner which will be presently described.

Two wires 19 and 19^a extend from the sockets 12 of the switch and lead to contact plates 20 and 21 which are positioned in the path of the plates 17 and 18 carried by the switch lever 13 so that when said lever is raised in a manner hereinafter to be described, the contact plates 17 and 18 will engage those 20 and 21 to close the motor circuit and open the signal circuit. When a train enters track section B and the switch lever is closed so as to separate the contacts 20 and 21 from those 17 and 18, it will be obvious that a circuit is completed through the wires 22 and 23. The current will flow through wire 23, into the wire 23^a then to 9^a and into the battery B'. From here, the current will pass into the electric motor and from there into wire 9 then to wire 22^a to return through wire 22. The motor shaft is equipped with a pulley wheel 51 to which is secured a cable 53, the free end of which is connected to the switch lever 13. Consequently, when the motor circuit is closed the switch lever will be lifted so as to disengage from the contact sockets 12 and cause contacts 20 and 21 to engage those 17 and 18 carried by the lever. When these two pairs of contacts meet, the motor circuit will be established which may be closed from either blocks A or C. The train departing from block B and entering block C will close the circuit through the pair of rails and current will pass from wire 26 into one of the switch sockets 12 from whence it will travel into contact plate 20 then into contact 18 carried by the lever and then through wire 9^a into the battery. From here, the current will flow out into the motor and return through the other post socket by way of contact plates 17 and 21 from where it will pass through wire 26' which connects to the rails. It will be noted that wire 26 alternates in its connection with the rails and is connected to both blocks A and C. When the switch lever 13 is raised, it will be understood that the signal circuit to be presently described, will be opened so that the signals will be inoperative when the motor is operating.

The signal circuit consists of a wire 7 connected to the lamp 2 at the top of one of the posts 1 down to lamp 5 in the sign box 3, then to the electrical alarm bell 6, and out through the base of the post across the track section B from which it is insulated to the wire 9^a which is connected to the battery B'. This wire 7 has a branch wire 7^a which extends to the other post 1 on the opposite side of the crossing and passes through the electric alarm bell 6 thereof, the lights 5 and 2 and back through wire 8 to one of the pivot posts of the switch as is clearly shown in Figure 1. A return wire 8' for the other

set of signals extends from the same pivot post of the switch 10 and is connected to the bell and lights of the signal first described. In order to complete a circuit for the signal from the switch to the battery, 70 a wire 27 is connected to the other pivot post of the switch and to the battery.

The operation of the apparatus when the train is upon either track is as follows: When a train enters section A, the signal 75 circuit will be closed by the engine in the well known manner through wires 26 and 26'. The switch lever 13 will be closed since it is normally held in this position by a coiled spring 28 connected thereto and to 80 the base of the switch as clearly shown in Figure 2. Therefore, current will pass through the wire 26 to one of the post sockets of the switch 10, through an arm of the lever and into the battery through the wire 85 27. Current will pass out of the battery through wire 9^a and into the signal wires 7 and 7^a where it will be conducted to the alarm bell and lights of the signals. The current will return from the signals through 90 the wires 8 and 8' to a pivot post of the switch through one of the switch arms of the lever and then into wire 26' which is connected to the blocks A. Consequently, both signals will be given while the train is 95 approaching the crossing.

As soon as the train reaches the crossing and is upon the block B, a circuit will be completed through wires 22 and 23. When the train first enters block B, the switch 100 lever 13 will be closed and current will pass through wires 23 into 23^a, then to 9^a where it is conducted into the battery. From the battery, it passes to the motor 50 to the wire 9 into 22^a to return to wire 22 thereby 105 completing the motor circuit. Immediately, the motor will begin to operate thereby pulling upon the cable 53 which raises the switch lever 13 from its post sockets and so that the contact plates 17 and 18 carried by the lever 110 will engage contacts 20 and 21 disposed in the paths of said plates. The switch lever upon disengagement of the switch post sockets will break the signal circuit and close a motor circuit through wires 26 and 26'. 115 When the train passes on to block section C, the motor will continue to operate since the circuit will be closed through the rails or blocks and current from the battery will travel through wire 9^a, contact plate 18 into contact 20 and into one post socket of the switch 10. From here, the current will pass through wire 26 through the engine on block C into wire 26'. This wire will carry the current to the other post socket of the 120 switch from where it will escape into the contact 21, then into contact 17, then to wire 9 into the motor and return to the battery. After the train has departed from block C, the motor will discontinue its opera- 125 130

tion and the coiled spring 28 will immediately return the switch lever to its normal position so that its arms engage the post sockets of the switch ready to complete a signal circuit when a train enters either of the blocks A or C.

The foregoing description and accompanying drawings have reference to what might be considered to be the approved or preferred form of my invention. I desire it to be understood that I may make such changes in the construction, combination, and arrangement of parts, material, dimension, etc. as may prove expedient and fall within the scope of the appended claims.

Having thus described my invention what I claim as new and desire to secure by Letters Patent, is:

1. In a signal of the class described, a plurality of separate track sections, one of which is disposed across a highway, a signal circuit including rail sections on opposite sides of the highway section and a source of electrical energy, a motor circuit including a motor having a drum attached to its shaft, a knife switch connected in both of said circuits, a flexible element connecting said drum to the lever of said switch to lift the

lever and open the switch to break the signal circuit when the motor is energized by the train entering the crossing section and the succeeding section.

2. In a signal of the class described, a plurality of track sections, one of which is disposed across a highway, a signal circuit including rail sections on opposite sides of the highway section and a source of electrical energy, a motor circuit including the track sections disposed across the highway and a motor having a drum attached to its shaft, a knife switch connected to both of said circuits, a spring connected to the lever of the switch for normally retaining the same in a position to close the signal circuit, a flexible element connecting said drum to the lever of said switch to lift the lever and open the switch to break the signal circuit when the motor is energized by the train approaching the highway section and the succeeding section.

In testimony whereof I affix my signature in presence of two witnesses.

ELBERT MONROE TOLSTON.
